METHOD OF CHLORINATING
HYDROCARBON MIXTURES

Lawrence H. Flett, Scarsdale, N. Y., assignor to
Allied Chemical & Dye Corporation, New York,
N. Y.

Application May 22, 1945, Serial No. 595,172

15 Claims. (Cl. 260—505)

1 The present invention relates to improvements in the method of chlorinating a hydrocarbon mixture of the type of a petroleum distillate.

It relates more particularly to improvements in the method of chlorinating such hydrocarbon mixtures in connection with the manufacture of nuclearly substituted aromatic sulfonates which are valuable detergents and wetting, emulsifying, and the like agents. One process for the manufacture of such nuclearly substituted aromatic sulfonates involves chlorinating a hydrocarbon mixture of the type of a petroleum distillate; condensing resulting chlorinated hydrocarbons with an aromatic compound with the aid of a condensation catalyst of the Friedel-Crafts type, such as anhydrous aluminum chloride or anhydrous zinc chloride, to form a mixture containing aromatic compounds having nuclear substituents; sulfonating a resulting mixture of nuclearly substituted aromatic compounds; and recovering the resulting mixture of sulfonic acids, preferably in the form of their salts, such as their salts with alkali metals. The invention relates particularly to improvements in the chlorination step of said process whereby advantages are secured in the manufacture of the mixtures of nuclearly substituted aromatic sulfonates. (Since the nuclear substituents are derived from hydrocarbon mixtures of the type of petroleum distillates, and accordingly are to a considerable extent aliphatic acyclic and/or alicyclic in nature, the nuclearly substituted aromatic sulfonates have come to be known in the art as "alkyl aromatic sulfonates," the term "alkyl" being used in a generic sense to denote a nuclear substituent radical derived from the hydrocarbon mixture. Accordingly, the nuclearly substituted aromatic compounds will be referred to herein as "alkyl aromatic compounds" and the term "alkyl" will be employed in said generic sense.)

An object of the invention is to provide improvements in the chlorination of hydrocarbon mixtures of the type of petroleum distillates, whereby mixtures of chlorinated hydrocarbons are obtained having a relatively low aniline point. It is a further object of the invention to provide improvements in the step of the above process in which the hydrocarbon mixture of the type of a petroleum distillate is chlorinated, whereby mixed alkyl aromatic sulfonates possessing excellent properties may be obtained in high yields. (The term "mixed" is employed herein in the sense of "mixtures.") A more specific object of the invention is to provide improvements in the chlorination step of the process of pre-

2 paring mixed alkyl aromatic sulfonates involving chlorinating a paraffinic petroleum hydrocarbon distillate in which the hydrocarbons contain an average of 7 to 35 carbon atoms, condensing resulting chlorinated hydrocarbons with benzene, phenol, or naphthalene, sulfonating the resulting mixed condensation product, and recovering the mixed sulfonation product, preferably in the form of an alkali metal salt; the improvements resulting in products of high quality which are obtained in excellent yields.

Other objects of the invention will in part be obvious and will in part appear hereinafter.

The mixed alkyl aromatic sulfonates with which the present invention is particularly concerned are preferably derivatives of aromatic compounds of the benzene, naphthalene, and diphenyl series. Thus the products may be derivatives of benzene, naphthalene, diphenyl, their homologs, or substituted members of the series to which these compounds belong in which the substituents may be, for example, halogens or hydroxyl, aroxy, alkoxy, lower alkyl, or carboxyl radicals which are present as nuclear substituents. Where the aromatic compounds are substituted, they preferably contain but one substituent. As suitable substituted aromatic compounds there may be mentioned phenol, cresol, chlorbenzene, toluene, xylene, resorcinol, hydroxydiphenyl, phenetole, and salicylic acid.

As pointed out above, the alkyl groups or side-chains present in the sulfonates are derived from a hydrocarbon mixture of the type of a petroleum distillate; for example, a kerosene fraction or a "white oil" fraction of petroleum, or a Fischer-Tropsch reaction product, preferably a distillate of a paraffinic petroleum (that is, a distillate of a paraffin-base petroleum).

In the manufacture of mixed alkyl aromatic sulfonates having the desired type of alkyl group and therefore having desirable properties, the manner in which the chlorination of the hydrocarbon mixture is carried out is important. References in the literature disclose that when chlorinating a hydrocarbon mixture for the purpose of finally replacing a hydrogen atom of the hydrocarbon molecules with some other radical such as the hydroxyl group, the best yields of the desired products are obtained when, at the end of the chlorination reaction, the amount of organically combined chlorine in the chlorinated hydrocarbon mixture is much less than that which corresponds to one atom of chlorine per molecule of hydrocarbon. That chlorination of this nature, which is conveniently termed "un-

chlorination," should result in a high proportion of desired products from hydrocarbon mixtures is also supported by theoretical considerations.

As is pointed out in my United States Patent No. 2,247,365, issued July 1, 1941, I have found, by chlorinating a hydrocarbon mixture of the type of a petroleum distillate, such as a kerosene or "white oil" fraction of petroleum, and preferably a paraffinic petroleum hydrocarbon distillate, to such an extent that the amount of chlorine which has become combined organically in the mixture is more than that which would be so combined if each hydrocarbon molecule present in the mixture were converted to its corresponding monochloride, that a chlorinated mixture is obtained which can be used successfully for the production of desirable mixed alkyl aromatic sulfonates with exceptional surface-active properties, and that these sulfonates are obtainable in greatly increased yield, based on the amount of hydrocarbon mixture employed, than when an "underchlorinated" hydrocarbon mixture is used. Hereinafter a chlorinated mixture containing an amount of organically combined chlorine which exceeds that which would be present if the mixture consisted of monochlorinated hydrocarbons only is said to be "overchlorinated."

When a hydrocarbon mixture of the type of petroleum distillate is subjected to overchlorination by slowly introducing chlorine into a large amount of liquid hydrocarbon mixture until the desired degree of chlorination is attained, a considerable period of time is required for the operation on a commercial scale. For example, 8 to 10 hours may be required for the overchlorination of a commercial batch of kerosene. If an attempt is made to reduce the period of chlorination by introducing the chlorine rapidly into the hydrocarbon mixture, a number of disadvantages result. Aside from the operating difficulties which result from the highly exothermic nature of the chlorination reaction, in some cases leading to flashing, a serious disadvantage is the marked lowering of the yield of mixtures of alkyl aromatic sulfonate obtained from the resulting chlorinated hydrocarbon mixture. The disadvantages, furthermore, increase with increased chlorination temperatures. Thus I have found, when kerosene is overchlorinated by passing chlorine, in substantially the amount required for overchlorination, rapidly into the kerosene, the yield of chlorinated kerosene is substantially the same as the yield of chlorinated kerosene obtained by the slow introduction of chlorine, but the aniline point of the resulting rapidly chlorinated kerosene is generally much higher and the yield of alkyl aromatic sulfonate obtained from said rapidly chlorinated kerosene is much lower.

I believe an important difference in the result obtained lies in the fact that the rapid introduction of the total amount of chlorine required for overchlorination results in an uneven distribution of the chlorine among the various molecules of hydrocarbon, with the result that a relatively larger proportion of hydrocarbon molecules are left unchlorinated and a relatively larger proportion of the hydrocarbon molecules are polychlorinated than when chlorine is slowly introduced.

The present invention is based upon the discovery that chlorination of the hydrocarbon mixtures of the type herein defined can be effected by the rapid introduction of chlorine into the hydrocarbon mixture in the liquid phase if the chlorine is introduced in portions of the total

amount effective for the chlorination and if the first portion introduced does not exceed an amount effective to chlorinate the hydrocarbon mixture to a degree not exceeding that corresponding with 55% chlorination and preferably not exceeding that corresponding with 35% chlorination. In many cases the first portion does not exceed an amount effective to chlorinate the hydrocarbon mixture to a degree not exceeding that corresponding with 15% chlorination. The actual amount of chlorine introduced relative to the amount of hydrocarbon mixture will depend upon a number of factors, including intimacy of contact of the chlorine and liquid hydrocarbon mixture, and the chlorination temperature.

Without limiting the invention to any theoretical considerations, I believe the advantageous behavior of the hydrocarbon mixtures, when subjected to chlorination by the procedure of the present invention, in connection with the production of chlorinated hydrocarbon mixtures containing an amount of organically combined chlorine corresponding with at least 75% chlorination, is related, at least in part, to the fact that the material subjected to the treatment is a mixture of hydrocarbons, some of which are more readily chlorinated than others. The chlorination of the more readily chlorinated components of the hydrocarbon mixture in a preliminary stage of the process, in accordance with this invention, seems to influence the distribution of subsequently added chlorine favorably, as a result of which a greater proportion of the individual hydrocarbon molecules is chlorinated and a lesser proportion is left unchlorinated than when the total amount of chlorine necessary for effecting said degree of chlorination is introduced all at once.

The process of the present invention may be carried out in various forms of apparatus. Thus the apparatus may include a plurality of separate chlorination units through which the hydrocarbon mixture to be chlorinated is passed in succession; it may include a single chlorination apparatus through which the hydrocarbon mixture to be chlorinated is repeatedly passed; it may include a single chamber provided with separate chlorine inlets spaced successively along the line of flow of the hydrocarbon mixture; or other forms which will be obvious to those skilled in the art.

It has been found that best results are obtained when the chlorination is divided up into two or more chlorination steps. After the preliminary chlorination to a limited degree, the next chlorination step may rapidly introduce the greatest proportion of the chlorine without disadvantageous results. When overchlorinating, it is advantageous to follow by one or more additional introductions of lesser proportions of chlorine. To assure rapid reaction, the hydrocarbon mixture and chlorine are advantageously brought into immediate intimate contact. Preferably the chlorination is carried out in such manner that the hydrocarbon mixture of the type of a petroleum distillate is passed in a continuous stream through a plurality of successive chlorination zones and portions of the total amount of chlorine are successively introduced and caused to react with the hydrocarbon mixture in said zones, so that the stream of hydrocarbon mixture reacts with successive portions of the total amount of chlorine.

The continuous chlorination procedure of the

present invention offers a number of economic and operating advantages as compared with discontinuous processes wherein chlorination is effected by passing chlorine gas into a batch of kerosene until the desired degree of chlorination has been reached. These advantages might be exemplified as follows: For the same volume of production, a much smaller size chlorinator is needed for continuous chlorination. This reduces the initial equipment investment and also maintenance costs. The reduced size of the chlorinator makes it economically feasible to construct it from highly corrosion-resistant materials, e. g., glass or porcelain, which would be impractical for the large size equipment needed for discontinuous batch chlorination. The continuous chlorination is easier to control. This makes it possible to produce a more uniform product. The continuous chlorinator can be fitted with automatic labor-saving control devices with obvious advantages as to cost and quality of the final product. Due to the small amounts of material being processed at any given instant, hazards due to fire are much less with the continuous chlorinator. The continuous chlorination process produces the hydrogen chloride, which is formed as a byproduct of the chlorination reaction, at a more constant, steadier rate, thus facilitating its recovery, e. g., as an aqueous solution of uniform hydrogen chloride content.

A further important advantage of the present invention is the possibility of carrying out the chlorination of petroleum hydrocarbon fractions at temperatures above the ordinary temperatures, e. g., at 60° to 200° C., with the attendant advantages of high temperature operation and without certain disadvantages inherent in bulk chlorination at such higher temperatures. These disadvantages are: decomposition reactions during the chlorination step, objectionable dark color of final alkyl aromatic sulfonate product, the fire hazard mentioned above which becomes particularly acute at higher temperatures, and extreme difficulties in controlling flashing and decomposition.

The process of the present invention has the following additional advantages: The chlorination is easier to control, as the heat evolution due to chlorination occurs in a plurality of reaction zones rather than in a single zone; there is less danger of excessive local overheating with attendant decomposition of the hydrocarbons and formation of soot. As a consequence, operation at higher temperatures is facilitated with the additional benefits accruing from the use of the higher temperatures. In addition, continuous chlorination in a plurality of zones has the advantage that the rate of kerosene flow can be made much greater with the result that a much greater output can be obtained from the chlorinating apparatus. For example, the maximum output of three individual chlorination units connected together in series to give continuous chlorination in a plurality of zones is considerably greater than that of the same three chlorination units when each is operated separately to obtain continuous chlorination in a single step.

It is advantageous to carry out the chlorination of the hydrocarbon mixture, each as a kerosene or "white oil" fraction of petroleum, for the most part, and preferably for substantially the entire chlorination period, at a temperature which is between 60° and 200° C. For the chlorination of such fractions of petroleum distillates,

chlorination temperatures of about 60° to 175° C. and preferably between 110° and 155° C., are employed with advantage. The optimum chlorination temperature varies with the hydrocarbon mixture being chlorinated and with the degree of chlorination. By reason of the fact that the present invention makes possible rapid chlorination of the hydrocarbon mixtures, it is possible to operate at such high temperatures. The chlorination can be completed before substantial decomposition of the chlorinated product occurs. The use of high temperatures also aids in the rapidity of the chlorination.

The chlorination may be carried out with the aid of chlorine carriers, catalysts, or adjuvants, such as, for example, phosphorus trichloride, iodine, sunlight, etc. The extent and rate of chlorination of the hydrocarbons can be controlled by means, such as adjustment of the ratio of weights of chlorine and hydrocarbon mixture which intermingle in the reacting space in a given unit of time, and by stimulation of the reaction by presence in the reacting space of a carrier, catalyst or adjuvant. It is not necessary in accordance with the present invention that carriers, catalysts, or adjuvants be employed; however. As evident from certain of the following specific examples, the process can be operated efficiently in the dark and in the absence of added adjuvants or carriers.

The present invention may be employed for the preparation of mixtures of alkyl aromatic sulfonates wherein the hydrocarbon mixture of the type of a petroleum distillate is chlorinated to various degrees. Thus it may be employed in connection with the preparation of mixtures of alkyl aromatic sulfonates in which a petroleum distillate of the type herein described is underchlorinated or is overchlorinated; that is in which the petroleum distillate is chlorinated to an extent less than "100 per cent chlorination" or greater than "100 per cent chlorination." (Throughout this specification and the claims, per cent chlorination is on a molar basis. It refers to the per cent ratio between the actual increase in weight due to chlorination of an amount of hydrocarbon distillate corresponding to the average molecular weight of the hydrocarbons in the distillate and the expected increase in weight of the same amount and kind of hydrocarbon distillate if every hydrocarbon in said amount of hydrocarbon distillate were converted to its corresponding monochlor hydrocarbon. Thus, the per cent chlorination may be expressed by the formula:

$$\frac{I}{I+100} \times 100$$

where 34.5 represents the increase in weight of an average molar quantity of hydrocarbon mixture if all the hydrocarbons in this quantity of mixture were converted to monochlor hydrocarbons only, and I represents the actual increase in weight of an average molar quantity of hydrocarbon mixture due to chlorine which is caused to become organically combined in the hydrocarbons of the quantity of mixture, by the chlorination.) The present invention is of particular advantage in connection with the chlorination of the hydrocarbon mixtures to a degree corresponding to at least 75 per cent chlorination; and more particularly to a degree corresponding to more than 100 per cent chlorination, but not more than 200 per cent chlorination. Within these limits it is preferred to chlorinate the hy-

drocarbon mixture to a degree corresponding to not more than 175 per cent chlorination. Especially valuable results are obtained when the chlorination is carried out to a degree corresponding to between 110% and 150% chlorination, or more specifically to a degree corresponding to about 120% chlorination.

The hydrocarbon mixtures employed in the present process, such as petroleum distillate, are complex mixtures whose composition is not definitely known. The approximate composition of petroleum distillates is determined by reference to the boiling points and the other physical properties of the compositions. Ordinarily, the petroleum distillates employed in the making of the alkyl aromatic compounds will boil over ranges the lower boiling points of which are not below 80° C. at atmospheric pressure, and the upper boiling points of which are not above 350° C. at 22 mm. absolute pressure. For the manufacture of products designed for general detergent use, it is preferred to employ petroleum fractions which are derived from Pennsylvania, or Mount Pleasant, Michigan, type petroleums and which fractions boil for the most part over a temperature range lying between 180° and 300° C., and are preferably composed predominantly of open-chain and cyclic non-aromatic, non-olefinic hydrocarbons which boil within the range 180° to 280° C. (It is noted that, where ranges are given throughout the specification and the claims, the range includes the limits.)

While the process of the present invention is of particular value in connection with the production of alkyl aromatic sulfonates from chlorinated hydrocarbon mixtures of the type referred to above, the invention is not limited thereto, since it provides chlorinated hydrocarbon mixtures of low aniline point, which are valuable for the preparation of other products in view of the greater distribution of chlorine among the individual molecules of hydrocarbons in the mixtures.

The aniline point, mentioned above in connection with chlorinated hydrocarbon mixtures, refers to a determination made as follows: A chlorinated hydrocarbon material to be tested is freed from all traces of dissolved hydrogen chloride by bubbling a current of air through it for at least 10 minutes. Then in a dry test-tube a convenient volume, e. g., 5 ccs. of the aerated sample, is mixed with an equal volume of freshly distilled aniline. If necessary the mixture is warmed to obtain a clear homogeneous solution. While the solution is stirred with a thermometer it is cooled slowly and the temperature is noted at which the solution becomes so opaque, due to the development of turbidity, that the bulb of the thermometer is no longer clearly visible. This temperature is known as the aniline point. I have found that the aniline point is a measure of the content of desired alkyl chlorides, presumably alkyl mono-chlorides, in chlorinated hydrocarbon mixtures of the type of petroleum distillates. Thus, two chlorinated kerosenes produced from the same kerosene under different conditions but chlorinated to the same degree, as evidenced by the same specific gravity, will lead to different yields of alkyl benzene sulfonates useful as detergents, if the aniline points of the chlorinated kerosenes are different, the higher yield of desirable alkyl benzene sulfonates generally being obtained from the chlorinated kerosene of the lower aniline point. In a typical determination two portions of a kerosene were chlorinated under

differing chlorination conditions until the increase in specific gravity due to chlorination was 0.1305 in each case. The aniline point of one chlorinated kerosene was 12.2° C.; that of the other chlorinated kerosene was 37.0° C. When converted to keryl benzene sulfonates in the same manner, the yield in grams of organic sulfonate per kilogram of kerosene subjected to chlorination was 751, in the case of the former, as compared with 453 in the case of the latter. A feature of the procedure of the present invention is the relatively low aniline points of the resulting chlorinated hydrocarbon mixtures.

The process of the present invention may be practiced in various ways. In general, a stream of hydrocarbon mixture of the type referred to above is passed in liquid phase through a chlorination chamber or zone, chlorine is introduced into the hydrocarbon mixture in said chamber or zone in an amount not exceeding that effective to chlorinate the hydrocarbon mixture to a degree corresponding to 55% chlorination (and preferably not exceeding that effective to chlorinate to a degree corresponding to 35% chlorination) while in said zone, and additional chlorine is then introduced into a flowing stream of the resulting partially chlorinated hydrocarbon mixture while maintaining the temperature of the latter reaction mixture within the range 60° to 200° C., the total amount of chlorine relative to the amount of hydrocarbon mixture employed in the chlorination being at least sufficient to result in a chlorinated hydrocarbon mixture containing an amount of organically combined chlorine corresponding to 75% chlorination.

As a result of the chlorination, hydrogen chloride is formed. Further, unless extreme care and highly efficient operation are employed, the hydrogen chloride given off by the reaction mixture generally contains some chlorine. In addition, particularly at elevated chlorination temperatures, the lower boiling constituents of the hydrocarbon mixture and/or chlorinated hydrocarbons may, to some extent, appear in the exit gases. An advantageous method of practicing the present invention involves contacting or scrubbing the exit gases with the hydrocarbon mixture to be chlorinated. By coordinated regulation of the chlorine charged to the main chlorinators, the amount of chlorine in the exit gases from said chlorinators may be limited so that the amount present in the exit gases does not exceed that required to chlorinate the hydrocarbon mixture in the scrubber to the limited extent required by the present invention. Thus, the scrubber may be employed as the initial chlorinator in accordance with the present invention and at the same time can serve to remove from the hydrogen chloride gas the vapors of hydrocarbons and/or hydrocarbon chlorides as well as unreacted chlorine, which would reduce the utility of the hydrogen chloride.

To secure intimacy of contact between the liquid material being chlorinated and the chlorine gas, the chlorination chamber may be provided with packing material of various types. An advantageous method of securing intimate contact is to employ a high rate of flow of the liquid hydrocarbon mixture to be chlorinated. By proper selection of the size and shape of the chlorinating apparatus and the speed of flow of the liquid hydrocarbon mixture, the process may be operated under conditions of turbulent flow of the liquid hydrocarbon mixture in an unpacked chlorination vessel or zone. An advantageous

method of carrying out the process involves passing the liquid hydrocarbon mixture through an unobstructed chlorination zone which is of greater length than the effective average width of the stream of liquid hydrocarbon mixture, at a relatively high average velocity. (The effective average width of the stream is the average width, e. g. diameter, of the free space through which the stream flows; thus, in case of a packed tube or tower it is much smaller than the actual diameter of the tube or tower.) Preferably, the average velocity exceeds 50 feet per hour and may be as high as 20,000 feet per hour. Operations at average velocities of 50 to 5,000 feet per hour can be readily carried out. (As employed herein, the term "average velocity" is the velocity represented by the equation:

$$A = \frac{C \cdot L}{V}$$

where A equals average velocity measured in feet per hour; C equals cubic feet of liquid per hour passing through the chlorination zone; L equals length in feet of the chlorination zone; and V equals volume of liquid hydrocarbon mixture in the chlorination zone at any instant, measured in cubic feet.) The particular average velocity employed in a given case will depend upon other factors of the process, such as intimacy of contact between the liquid hydrocarbon mixture and the chlorine, the rate of chlorine flow, the temperature of the chlorination, the degree to which the chlorination is carried out, and the nature of the hydrocarbon mixture undergoing chlorination. Thus for the chlorination of a petroleum distillate boiling for the most part over a temperature range (at atmospheric pressure) lying between 180° and 300° C., which has been given an initial chlorination to a degree not exceeding that corresponding with 55% chlorination and preferably not exceeding that corresponding to 35% chlorination, a stream of the partially chlorinated hydrocarbon mixture in liquid phase may be chlorinated to a degree corresponding to 75% to 200% chlorination by passing chlorine into said partially chlorinated hydrocarbon mixture while the latter is flowing at an average velocity of 50 to 1000 feet per hour and preferably from 50 to 600 feet per hour. The chlorination temperature is controlled so as to prevent the peak temperature of the chlorination from exceeding 200° C., and preferably 175° C. Ordinarily, in connection with rapid flow of the partially chlorinated hydrocarbon mixture, the chlorination is carried out at a temperature of at least 80° C., more particularly at least 100° C., and preferably at least 110° C.

In order that the invention may be understood more fully, reference should be had to the following examples and the accompanying drawings in which:

Fig. 1 is an elevation of one form of apparatus for carrying out the chlorination;

Fig. 2 is an elevation partly in section of another form of apparatus for carrying out the chlorination;

Fig. 3 is a sectional elevation of a modified form of the chlorination apparatus shown in Fig. 2;

Fig. 4 is an elevation partly in section of a modified form of the chlorination apparatus shown in Fig. 1.

For convenience, where a kerosene fraction of petroleum is used in the process disclosed in the examples, the product obtained by chlorinating this fraction is termed "keryl" chloride, and the

product obtained by condensing the "keryl" chloride with benzene, for example, is termed "keryl" benzene. It will be understood that the specific character of the "keryl" chlorides and "keryl" benzenes or other "keryl" aryl products will be dependent upon the particular kerosene used and the manner in which the process is carried out.

The apparatus shown diagrammatically in Fig. 1 consisted of a chlorination chamber in the form of a vertical tower or pipe 1 having an inlet 6 for the liquid hydrocarbon mixture or partially chlorinated hydrocarbon mixture, an inlet 2 for chlorine, and an outlet 3 for chlorinated kerosene and exit gases. The chamber 1 was enclosed in a temperature-regulating jacket 5 through which cooling water or steam could be circulated to provide for regulation of the temperature in the chamber 1. The apparatus included a second similar chamber or tower 11, having an inlet 10 for chlorinated kerosene, an inlet 12 for chlorine, and an outlet 13 for the chlorination reaction mixture. The outlet 3 from the chamber or tower 1 was connected with a separator 7 leading to an outlet 23 for the gaseous portion of the reaction mixture (hydrogen chloride, excess chlorine and vapors of hydrocarbons and/or chlorinated hydrocarbons), and a liquid duct 8 which was connected with the inlet 10 of the chamber or tower 11. A similar separator 17 connecting with the outlet 13 was provided for separating the gaseous portion of the chlorination reaction mixture into a gaseous or vapor portion, which was carried off through outlet 24, and a liquid portion comprising chlorinated kerosene, which was withdrawn through duct 18. A receiver 19 for the chlorinated kerosene was connected to the duct 18 and was provided with an outlet 25 for residual gases and vapors. The outlets 23, 24 and 25 were connected to a header 26 which carried the gases and vapors into a scrubber 30 which was in the form of a chamber or tower having an inlet 31 for hydrocarbon mixture and an outlet 32. A separator 33 was connected to the outlet 32 for separating the material flowing from the scrubber into a gaseous portion, which was removed through an outlet 36, and a liquid portion (partially chlorinated hydrocarbon mixture) which was carried by a pipe 34 to the inlet 6 of the chamber or tower 1. Valves 40 and 41 were provided in the supply line 45 for hydrocarbon mixture whereby the hydrocarbon mixture could be introduced into either or both of the tower 1 and scrubber 30, as desired. Thermometers 8 and 14 were provided for measuring the temperature of the chlorination reaction mixtures leaving the chlorination chambers 1 and 11, and additional thermometers 9, 20, 37 and 38 were provided for measuring the temperature of the material flowing through the system at the points indicated in Fig. 1 of the drawing.

Various means were provided for securing intimate contact of the chlorine, introduced into the chambers or towers 1 and 11 through inlets 2 and 12, with the liquid introduced through inlets 6 and 10. These included a porous Alundum disc or a closed tube having a multiplicity of small holes near the closed end thereof.

In operating this apparatus, a stream of hydrocarbon mixture of the type above referred to was introduced into the tower 1 and allowed to flow over into tower 11 and on through the duct 18 into the receiver 19 and out through open valve 46. Streams of chlorine were introduced

into the towers 1 and 11 through inlets 2 and 12 which were controlled by suitable valves. Cooling water was circulated through the jackets 5 and 15. The scrubber 30 was filled with kerosene and valve 40 was closed.

After a short time, excess chlorine and hydrogen chloride gases given off by the chlorination taking place in chambers 1 and 11 were passed into the scrubber 30, the valve 40 was opened and the valve 41 was closed. The flow of hydrocarbon mixture through the inlet 31 of the scrubber 30 and the flow of chlorine through the inlets 2 and 12 were adjusted so as to have excess chlorine in the gases entering the scrubber 30 through header 26 and inlet 35, but in an amount insufficient to chlorinate the hydrocarbon mixture during its passage through the scrubber to a degree higher than that corresponding with 55% chlorination. By adjustment of the rates of chlorine streams introduced through inlets 2 and 12 the partially chlorinated kerosene entering the towers or chambers 1 and 11 was further chlorinated to an ultimate degree such that the chlorinated kerosene passing into receiver 19 contained an amount of organically combined chlorine corresponding with substantially 120% chlorination. When this state was reached, valve 46 was adjusted to collect chlorinated hydrocarbon in receiver 19, from which it was drawn off at intervals.

Example 1

Kerosene was chlorinated in a specific embodiment of the apparatus of Fig. 1 in the following manner. The kerosene was obtained from the Cities Service refinery at Titusville, Pennsylvania. This kerosene had a density of 0.7888 at 24° C. and an aniline point of 72.4° C. Its boiling characteristics were as follows:

	° F.
Initial boiling point	366
5% distilled	378
10% distilled	387
50% distilled	432
90% distilled	496
95% distilled	516
Maximum distillation temperature	538

The specific embodiment of the apparatus included water-cooled towers 1 and 11, each constructed of a Pyrex glass pipe 4 feet long and 2 inches in diameter, which were packed with $\frac{1}{2}$ inch porcelain Berl-saddle packing material; and a scrubber 30 constructed of a Pyrex glass pipe 4 feet long and 3 inches in diameter, which contained no packing material and was cooled by contact with the atmosphere.

Operation was started in the manner described above, the temperature at the top of towers 1 and 11, as shown by thermometers 4 and 14, was allowed to rise to about 100° C. When the scrubber 30 and towers 1 and 11 were operating, the kerosene rate of flow into scrubber 30 was set at 41 pounds per hour. The chlorine was introduced in gas form under a gage pressure of about 25 pounds per square inch. The chlorine rate of input through inlets 2 and 12 was adjusted until keryl chloride of a specific gravity of 0.918 was obtained in receiver 19 (corresponding with about 120 per cent chlorination of the kerosene), and partially chlorinated kerosene of a specific gravity of 0.793 (corresponding with about 4.6 per cent chlorination of the kerosene) was discharged from the scrubber 30 into tower 1. The keryl chloride discharged from tower 1 into tower 11

had a specific gravity of 0.882 (corresponding with about 81 per cent chlorination). By adjustment of the cooling water in jackets 5 and 15, the temperatures at the tops of the towers were held at about 110° C.

Continuous operation of the apparatus was then carried out in this manner with steady production of keryl chloride of about 0.918 specific gravity and having an aniline point of 7.5° C. The average velocity of the liquid passing through tower 1 was 85 feet per hour.

For determination of the yield of keryl benzene sulfonate obtainable from the resulting keryl chloride, a portion of it was subjected to the following treatment:

Five hundred parts of the keryl chloride were added to an agitated mixture of 1,000 parts of benzene and 25 parts of anhydrous aluminum chloride. (Parts, wherever indicated herein, are by weight unless specified otherwise.) The mixture was heated to 45° C., and held at 45° C. to 50° C. for about a half hour. The resulting condensation reaction mixture was allowed to stand over night (16 hours) and the oily upper layer was separated from the tarry bottom layer. The separated oily layer was fractionally distilled to remove excess benzene, first at atmospheric pressure and then at reduced pressure (up to 85° C. at 30-50 mm. pressure). The pressure was then adjusted to 5 mm. of mercury and a small fraction of distillate boiling up to 95° C. was collected and saved as "recovered kerosene." Distillation was then continued with recovery of all material boiling between 95° and 235° C. at 5 mm. pressure; it consisted essentially of keryl benzene.

The resulting keryl benzene was refined and sulfonated in the following manner: A 100-gram portion of the keryl benzene was stirred with 10 ccs. of 100 per cent sulfric acid, heated to 40° C., and agitated at 35 to 45° C. for a half hour. The resulting mixture was transferred to a separatory funnel, allowed to stand for a half hour, and the separated lower, colored acid layer was drawn off and discarded. The upper, refined keryl benzene layer was then placed in a glass sulfonating flask and 140 grams of 100 per cent sulfric acid was added with agitation. Sulfonation of the keryl benzene was completed by warming the mixture to 55° to 60° C. and maintaining the agitated mass at the temperature for about one hour. The sulfonation reaction mixture was then run into 200 cc. of water while simultaneously adding sufficient 25 per cent sodium hydroxide solution to maintain the mass substantially neutral to phenolphthalein. The solution was then brought to substantial neutrality (light green on nitrazine yellow paper) by necessary additions of sulfric acid or sodium hydroxide solutions.

The neutral slurry was analyzed as follows: a 10 cc. portion of the neutral slurry was transferred to a tared beaker, weighed, and evaporated (at 105° to 135° C.) to constant weight. From the weight of the dry sample, the total solids present in the slurry was calculated. The sodium-keryl benzene sulfonate content of the solids was determined by dissolving in 10 ccs. of distilled water a one-gram sample of a drum-dried sample of the slurry; adding 100 ccs. of anhydrous ethyl alcohol; stirring; letting the mixture stand for 15 to 30 minutes; collecting the insoluble inorganic salts on a tared Gooch crucible; washing with several small portions of anhydrous ethyl alcohol; drying at 105° to 135° C.; and igniting at 600° to 700° C. for half an hour. The differ-

ence between the resulting weight of the salts and the weight of the sample was the weight of sodium keryl benzene sulfonate in the sample. Therefrom, the proportion of sodium keryl benzene sulfonate in the slurry was readily calculated.

The yield of sodium keryl benzene sulfonate produced from the chlorinated kerosene obtained in accordance with this example, when determined in this manner, was 855 grams per kilogram of kerosene. The product had excellent color, wetting power, and detergency.

As noted above, the chlorination process of the present invention may be carried out in other types of apparatus. For example, I may chlorinate a petroleum distillate to a limited extent by using the device shown in Fig. 2 and then attain the desired higher degree of chlorination by using the said device to contact the partially chlorinated petroleum distillate one or more additional times with chlorine gas. The degree of chlorination attained on each passage of the hydrocarbon fraction through the apparatus, in this case, depends to a large degree on the relative rates of flow of the hydrocarbon material and of the chlorine. Slower rates of chlorine flow will, other things being equal, reduce the degree of chlorination attained on contacting once with the hydrocarbon stream.

For countercurrent flow, the apparatus of Fig. 2 was operated as follows: Kerosene was introduced through a valved glass tube 113 into the top of a glass column 114. The column was not packed but was provided with numerous indentations to insure thorough mixing of the reacting streams. Valve 111 in a tube 116 connected to a flask 112 communicating with the column 114 was closed. The kerosene was maintained in the flask at the level shown by the line 115. The kerosene passed down the column 114 contacting an upward stream of chlorine gas which, in the form of fine bubbles, entered the reaction zone through a fiber glass sintered filter 117. The chlorinated kerosene was drawn off through valved tube 118 while the hydrogen chloride produced in the reaction was drawn off through the gas exit 119. Cooling water was passed through a jacket 120 to control the reaction temperature which was measured by a thermometer 121.

In carrying out a chlorination, the column was first filled three-fourths full of kerosene, and chlorine passed in until the kerosene had reached the desired degree of chlorination. During this period, the apparatus was warmed up to the desired temperature (86° to 86.5° C.). The flow of kerosene into the apparatus through tube 113 and withdrawal of chlorinated product through outlet 118 were then started. The flow of cooling water through the jacket 120 was adjusted so that the thermometer 121 indicated a temperature of about 86° C. After starting the flow of kerosene and making adjustments of temperature, flow of chlorine, etc., the product was discarded for a time (about 20 minutes) until it was felt that a stable state of conditions had been attained. Thereafter, chlorinated kerosene was collected.

For concurrent flow, the apparatus of Fig. 2 was operated as follows: Kerosene entered the device through the valved tube 118 and chlorinated kerosene was drawn off through tube 116. The valve in tube 113 was kept closed and the hydrogen chloride produced by the reaction was drawn off through the exit tube 119. The chlo-

rine gas entered through the fiber glass sintered filter 117.

In carrying out the concurrent chlorination of the kerosene, the column 114 was filled with the kerosene up to a short distance below its junction with the flask, and chlorine was passed in until the kerosene had reached the desired degree of chlorination. During this period, the apparatus was allowed to warm up to the desired temperature. The flow of kerosene into the apparatus and out, in chlorinated form, was then begun. The flow of cooling water through the jacket 120 was adjusted so that the thermometer 121 indicated the desired temperature. After starting the kerosene flow and making adjustments of temperature, chlorine flow, etc., the product was discarded for a time until it was felt that a stable state of conditions had been attained. The chlorinated kerosene was then collected.

The following example illustrates the use of the apparatus shown in Fig. 2 in this manner, employing countercurrent flow:

Example 2

25 The kerosene used in this example was the same as that used in Example 1.

The column 114 was filled with the kerosene up to a short distance below the flask 112 and chlorine was passed in at the rate of about 3.6 grams per minute for about 5 minutes. The temperature was allowed to rise to 60° to 70° C. The flow of kerosene into the apparatus through tube 113 and withdrawal of chlorinated product through tube 118 were then started. The rate of liquid flow through the column was adjusted so that approximately 18 grams of chlorinated kerosene were obtained during one minute. The diameter of tube 114 was 2 cm. The effective cross-section 30 of the kerosene stream was about 95% of the actual cross-sectional area. The average velocity was accordingly about 12.3 feet per hour. The rate of chlorine flow was maintained at about 3.6 grams per minute. The flow of cooling water 35 through the jacket was adjusted so that the thermometer 121 indicated a temperature of 60° to 70° C. The first 200 cc. of product were discarded during stabilization of conditions. Thereafter, a 3885 gram portion of chlorinated kerosene 40 having a specific gravity of 0.8440 (corresponding with about 52% chlorination) and an aniline point of 49.5° C. was collected.

This chlorinated kerosene product was stored in a loosely stoppered flask for about 20 hours 45 and then further chlorinated using the same general procedure as before. The chlorinated product was collected at the rate of about 15 grams per minute. In order to maintain the chlorination reaction at approximately the desired temperature of about 70° C., steam was passed through the jacket 20. The temperature registered by thermometer 21 was about 40° to 50° C. while the effluent product had a temperature of 90° C. About 3550 grams of a chlorinated product of specific gravity 0.8824 (corresponding with about 81% chlorination) and having an aniline point of 30.4° C. were obtained.

The chlorinated product so obtained was again stored in a loosely stoppered flask for about 20 hours and then further chlorinated once more, again using the same general procedure. The chlorine rate was about 2 grams per minute and the chlorinated product was collected at a rate of about 15 grams per minute. At the start of the chlorination, steam was run through the

jacket 120 for about 15 minutes to warm up the apparatus. The steam was then shut off. The heat of the chlorination reaction was sufficient to maintain a suitable temperature which registered as about 55° C. on the thermometer 21. The product obtained when operating under these conditions had a specific gravity of 0.9246 (corresponding with about 125% chlorination) and an aniline point of 7° C.

A portion of the chlorinated kerosene was condensed with benzene in the following manner: 608 grams of benzene and 15.2 grams of anhydrous aluminum chloride were agitated at room temperature in a glass flask and 304 grams of chlorinated kerosene (prepared as described above) were run in during the course of 20 minutes. The reaction mixture was warmed to 45° and agitated at 44° to 46° for an hour and a half. After allowing the mixture to stand about 16 hours, the lower tarry layer was separated by decantation and discarded. The remaining crude reaction product was distilled, first at atmospheric pressure to remove unreacted benzene, and then under reduced pressure. The fraction boiling from 80° C. at 4 mm. of mercury up to 255° C. at 20 mm. of mercury, absolute pressure, was collected separately for sulfonation.

100 grams of the distilled product were refined and sulfonated in the following manner: 100 grams of the distilled condensation product were agitated at room temperature for about three-quarters of an hour with 10 cc. of 100 per cent sulfuric acid. After standing for about half an hour, the acid layer was drawn off and discarded. The refined oily material was then agitated and sulfonated by adding 100 cc. of 100 per cent sulfuric acid at room temperature over a period of 10 to 20 minutes, and then warming the mass to 55° to 60° C. and agitating for one hour. After adding 1 cc. of water to the sulfonation mixture and agitating briefly, the mass was allowed to stratify for one hour. Three layers formed. The intermediate sulfonic acid layer was separated from the upper unsulfonated oil layer and the lower spent acid layer. The sulfonic acid layer was poured onto about 500 grams of cracked ice and the resulting solution was neutralized by adding 93 cc. of 50 per cent aqueous caustic soda. Sufficient sodium sulfate (anhydrous) was dissolved in the neutralized solution to bring the inorganic salt content of the solute up to about 60 per cent. The solution was then dried on a double drum drier to obtain a flaky product having excellent detergency and wetting power. The process of this example produced 784 grams of organic detergent material per kilogram of kerosene consumed.

Stepwise continuous chlorination may also be carried out in a modified form of the apparatus of Fig. 2 which is shown in Fig. 3. This involves a modified column 114' containing a plurality of spaced chlorine diffusers 117', 117'', and 117''', whereby several streams of chlorine are contacted successively with a stream of kerosene or other petroleum hydrocarbon mixture. In the operation of the modified apparatus, kerosene (for example) is introduced in a continuous stream into the bottom of the column 114'; as the kerosene flows upward through the column, it comes in contact successively with three independent streams of chlorine gas entering through fiber glass sintered diffusers 117', 117'', and 117'''. The chlorinated hydrocarbon material is separated from hydrogen chloride and any un-

reacted chlorine in the flask 112. The chlorinated hydrocarbon product is drawn off through outlet 116 while the gases pass out through the tube 119. As required, heating or cooling means (not shown) are used to aid in maintaining the temperature of the column within the desired temperature limits, depending upon the chlorination temperature and rate of flow of the reaction mixture through the apparatus.

Example 3

A mixture of kerosene of the type employed in Example 1 and "recovered kerosene" derived therefrom, containing 79 per cent of kerosene and 21 per cent "recovered kerosene," was chlorinated in an apparatus of the type shown in Fig. 3 to which a combined initial chlorinator and scrubber for the gases (similar to scrubber 30 of Fig. 1) was attached. The specific embodiment of the chamber 114' was in the form of a nickel tube 8 feet long and 4 inches in diameter provided with a chlorine inlet 117' at the bottom, a second chlorine inlet 117'' spaced 17½ inches above inlet 117', and a third chlorine inlet 117''' spaced 16½ inches above the second inlet. It was packed with ½ inch porcelain Berl saddles and was surrounded throughout its length by a series of three separate cooling jackets. For measurement of temperatures, thermocouples were inserted at spaced intervals along the length of the tube. The scrubber 30 consisted of a Pyrex glass tube 4 feet long and 4 inches in diameter which was enclosed in a steel temperature-regulating jacket through which water or steam could be circulated. The outlet 119 was connected to inlet 35 of the scrubber and the inlet 118' was connected to pipe 34 and valve 41 by duct 48. The scrubber 30 was also packed with ½ inch porcelain Berl saddles.

In the operation of the apparatus, the kerosene mixture (having a specific gravity of 0.788) was preheated to 135° C. and pumped into tube 114' through the line 45, duct 48 and tube 118. When the tube 114' was filled, chlorine was started in through inlet 117' and then through inlets 117'' and 117'''. When the keryl chloride leaving the chlorinator through exit line 116 had a specific gravity of about 0.900, the kerosene flow was gradually diverted to the scrubber 30, and after the scrubber 30 was in operation and liquid from the scrubber 30 was flowing through the pipe 34, valve 41 was shut and the kerosene mixture was then introduced into the system solely through inlet 31. By control of the chlorine introduced into the separate inlets 117', 117'', and 117''', and by suitable control of the cooling water in the jackets surrounding the chamber 114' the temperature was maintained within the desired range, as shown by the thermocouples. After equilibrium had been established, the operation of the apparatus was continued in the following manner: The kerosene mixture was introduced into the scrubber at a temperature of about 110° C. and at the rate of 183 pounds per hour. Chlorine was introduced through the inlet 117' at the rate of 38.5 pounds per hour, chlorine was introduced through the inlet 117'' at the rate of 18 pounds per hour, and chlorine was introduced through the inlet 117''' at the rate of 18.5 pounds per hour. The temperature of the partially chlorinated kerosene entering the tube 114' was about 84° C. and its specific gravity was 0.798 (corresponding with about 10% chlorination). The gases leaving the chlorination chamber through outlet 119 contained about 9% of chlorine. The

Average velocity of the liquid passing through the tube 114' was 173 feet per hour. The temperatures at various points within the tube 114', recorded by the thermocouples, were as set out in the following table:

Table I

Position of Thermocouple No.	Distance from Bottom of Tower, inches	Temperature, °C.

	77	111
	96	95

¹Inlet.

²Outlet.

The keryl chloride continuously produced in this manner had a specific gravity of 0.919. For determination of the yield of keryl benzene sulfonate obtained from said keryl chloride a portion of it was subjected to the treatment described in Example 1. The yield of sodium keryl benzene sulfonate thus obtained was 858 grams per kilogram of kerosene mixture subjected to chlorination.

Additional apparatus for carrying out stepwise continuous chlorination is disclosed in Fig. 4. It consists essentially of a plurality of chlorination chambers 130, 131, and 132 having means for flowing a stream of hydrocarbon, such as kerosene or white oil, successively through them; means for separately introducing a stream of chlorine gas into each chlorination chamber (shown as capillary tubes 136, 137, and 138) and means for removing the chlorination products from the apparatus (shown as discharge 141). Outlets 142, 143 and 144 for hydrogen chloride and residual chlorine are provided. Agitators 146, 147, and 148 are also provided to increase the contact between the hydrocarbon mixture and chlorine. The rate of chlorine flow is regulated by suitable devices (not shown). The rate of chlorine flow is not necessarily the same through all the various inlet tubes. The apparatus may be heated or cooled, as required, by any suitable temperature regulating means (not shown). The temperature may be varied from one chlorination zone to the next by suitable choice of the heating or cooling means.

The following examples illustrate the operation of the type of apparatus shown in Fig. 4:

Example 4

Kerosene having a specific gravity of 0.788 at 24° C., and a boiling range such that over 80% distilled within the range 194° to 256° C. with the 50% distillation point about 220° C., was first filtered through filtercel (a diatomaceous earth product) and then was run into glass chambers 130, 131, and 132, each of about one liter capacity and exposed to diffused daylight, until the overflow level was reached in each (about half full). The kerosene rate was then adjusted so that the rate of input (tube 134) and output (tube 141) flow was about 60 ccs. per minute. The chlorine input through tubes 136, 137 and 138 was then adjusted so that the rate was 5 to 6 grams of chlorine per minute into chamber 132. All three chambers were cooled somewhat, the temperature

being kept at about 97° to 105° C. in chambers 130 and 131 and about 100° to 108° C. in chamber 132. The chlorine used was purified by bubbling through concentrated sulfuric acid. After operating for about an hour, steady state conditions were established. About 500 grams of chlorinated kerosene were then collected. This chlorinated kerosene had a density of 0.918 at 24° C. (corresponding with about 120% chlorination) and an aniline point of 8.5° C. The partially chlorinated material flowing through tubes 142 and 143 had densities of about 0.829 and 0.859, respectively (corresponding with about 40% and 64% chlorination, respectively), after steady state conditions had been reached.

Example 5

Kerosene of the type employed in Example 4 was chlorinated at different temperatures in apparatus of the type shown in Fig. 4, in the presence of diffused daylight, by a procedure substantially like that described in Example 4, but differing therefrom in the following particulars: The uniform kerosene rate was adjusted so that the input (tube 134) and output (tube 141) flow was about 41 cc. per minute; the chlorine input through the tubes 136, 137 and 138 was adjusted so that the rate was 3 to 4 grams chlorine per minute into chambers 130 and 131, and about 6 to 7 grams chlorine per minute into chamber 132. When the specific gravity (determined at 24° C.) of the final chlorinated material had increased to 0.915 to 0.922, the chlorination was considered finished. Chlorinations were made at 60° to 61° C., 62° to 105° C., 99° to 101° C., 102° to 105° C., 100° to 121° C., 110° to 145° C., and 114° to 180° C.

Each of these batches of chlorinated kerosene was condensed with benzene in the following way: 608 grams of benzene and 15.2 grams of anhydrous aluminum chloride were placed in a glass flask and stirred. 304 grams of the chlorinated kerosene were then run in at room temperature during the course of 20 minutes. The temperature was then raised to 45° C. in 5 minutes and held at 44° to 46° C. for an hour and a half. The reaction mixture was then allowed to stand about 16 hours. The tar which separated out was drawn off and discarded. The remaining crude condensation product was then distilled by heating it to 100° C. at ordinary pressure to strip it of most of the unreacted benzene; then, to insure absence of substantial amounts of benzene from the desired keryl benzene fraction, the stripping was continued by reducing the pressure in the still first to 40 mm. and finally to 4 mm. of mercury absolute pressure while the temperature during this phase was allowed to drop somewhat, the final temperature being about 80° C. After this point, the distillate which came over between 80° and 238° C. at 4 mm. mercury pressure was collected as the desired keryl benzene fraction.

The several keryl benzenes thus prepared from the same kerosene by chlorination at different temperatures were next refined and sulfonated as follows: 100 grams of an alkyl benzene sample were agitated for three quarters of an hour at room temperature with 10 cc. of 100 per cent sulfuric acid. After allowing the mixture to stand for 30 minutes, the dark-colored acid layer was drawn off and discarded. The refined oil was then sulfonated by agitating it with 76 cc. of 100 per cent sulfuric acid for 1 hour at 55° to 60° C. The sulfonation mass was then al-

lowed to stratify for about 1 hour. Three layers formed. The intermediate sulfonic acid layer was separated from the upper unsulfonated oil layer and from the lower spent acid layer, diluted with about 400 cc. ice, and neutralized with 50 per cent aqueous caustic soda.

In each case, the yield in grams of organic sulfonate in the resulting neutralized solution was determined in the following way: An aliquot portion of the neutralized solution was evaporated to dryness and the residue weighed, using quantitative precautions. The total solids content of the neutralized detergent solution was then calculated. A one gram portion of the desired solids was dissolved in 10 ccs. of water and the inorganic salt was precipitated with 100 ccs. of anhydrous alcohol. The inorganic salt was collected in a Gooch crucible, and was washed with a little anhydrous alcohol, thereafter dried and weighed. The alcohol-soluble material was substantially all sodium keryl benzene sulfonate, and its yield was then readily computed. Sufficient sodium sulfate was then dissolved in each of the neutralized solutions to adjust the inorganic salt content of the solute to about 60 per cent. Each solution was then dried on a double-drum drier.

Each of the light-colored flaky products so obtained had excellent detergent properties. These keryl benzene sulfonate compositions were also compared for odor in the following manner: A 5-gram sample of a freshly dried composition was weighed out in a tall-form, 600 cc. glass beaker; 25 to 30 cc. of hot distilled water (90° to 95° C.) were poured onto the sample, and immediately thereafter the degree of unpleasant odor of the vapors from the solution was noted. A sample which was substantially devoid of odor was rated "good"; samples having unpleasant odors were rated according to increasing odor: "fairly good," "fair," and "poor."

The data obtained are reported in Table II. The favorable effect of temperatures of chlorination from about 100° to about 120° C. on yield of sodium keryl benzene sulfonate and on odor of the final sulfonate composition is definite and surprising.

Table II

Run No.	Temperatures			Specific gravity of Chlorinated Kerosene at 24° C.	Yield of Keryl Benzene Sulfonate (g. per Kilo of Kerosene Consumed)	Odor (Rated for Freedom from Kerosene-like Odor)
	Chamber 130 (°C.)	Chamber 131 (°C.)	Chamber 132 (°C.)			
1.	60	60	61	0.917	722	Poor.
2.	105	62	62	0.916	749	Fairly good.
3.	99	101	100	0.921	790	Do.
4.	105	102	102	0.916	798	Do.
5.	100	120	121	0.914	814	Good.
6.	110	144	145	0.916	749	Do. ¹
7.	114	177	180	0.916	763	Do. ¹

¹ These products, although free from kerosene-like odor, had a different, musty odor.

As shown in Table II, only one, or none, of the three chlorinating flasks in each of the runs #1, #2, #6 and #7 was maintained at a temperature between about 100° and about 120° C., and in these runs, the yields of keryl benzene sulfonate were less than yields of runs #4 and #5, in which all of the flasks were maintained at a temperature within the range about 100° to about 120° C. For obtaining the least kerosene-like odor, a chlorinating temperature in the upper part of the temperature range about 100° to

about 120° C. is desirable; thus in run #5 a product was obtained which had substantially no odor, and was superior in this respect to the products of runs #6 and #7 which had noticeable, musty odors, and to products of runs #3 and #4 which had distinct kerosene-like odors.

Stability of each sodium keryl benzene sulfonate composition to development of unpleasant odor during storage was tested by an accelerated aging process in which 5 grams of the composition were placed in a two-ounce stoppered bottle which was maintained at 80° C., and odor of the heated material in the bottle was noted at specified intervals; for example, every 24 hours. For comparative purposes a similar test was applied to a sodium keryl benzene sulfonate composition which was prepared from chlorinated kerosene prepared by a batch chlorination. The results of this aging test are shown in Table III:

Table III

Product of Run No.	Tested Period in Days	Odor Noted at End of Test Period
1.	10	Slight odor.
2.	10	Do.
3.	10	Very slight odor.
4.	10	Slight odor.
5.	10	Very slight odor.
6.	10	Do.
7.	10	Slight odor.
Batch Chlorination	4	Strong odor.
	10	Extremely strong odor.

It will be evident to those skilled in the art that the invention is not limited to the details of the foregoing illustrative examples and that changes can be made without departing from the scope of the invention.

The devices illustrated in the attached drawings are meant to illustrate various suitable apparatus for carrying out the chlorination of hydrocarbon mixtures in accordance with the present invention. No limitation as to the scope of the invention with regard to chlorination devices is to be deduced therefrom, however. Further, it is not intended to restrict the scope of the invention to chlorination devices made of any specific material. Other materials of construction

resistant to chlorine and hydrochloric acid may be used to equal advantage. For example, apparatus made from a nonresistant metal and lined with vitreous enamel, or other resistant material could be used.

Furthermore, it is not intended to limit the invention to processes of chlorination carried out at atmospheric pressure as the pressure within the apparatus may be greater or less than atmospheric without going outside the scope of the present invention. For example, superatmos-

pheric pressure may be used at elevated temperatures such that lower-boiling constituents of the hydrocarbon mixture would vaporize at atmospheric pressure.

Due to the limited solubility of chlorine gas in petroleum hydrocarbons, efficient operation of a continuous chlorination process makes it highly desirable to provide some means of insuring intimate contact between the stream of chlorine gas and the stream of hydrocarbon fraction. Various nozzles can be used for the chlorine inlets employed in accordance with my invention. For example, the chlorine may be fed through a glass capillary or through a sintered glass filter or through a closed pipe having a number of small openings at the closed end or through a porous ceramic ware inlet, such as an alundum cup or disc. In any case, it is preferred to contact the chlorine with the kerosene in such a way that the mingling of the chlorine with the kerosene is effected with greatest possible speed and completeness. Various devices other than those described are well known to those skilled in the art.

While the preferred embodiment of the invention involves the introduction of chlorine into a flowing stream of the hydrocarbon mixture, it is not essential that the initial chlorination to the limited extent be carried out in this manner. Thus, the initial chlorination may be carried out in a static body of hydrocarbon mixture (for example, in one of several alternate tanks of hydrocarbon mixture from which the partially chlorinated hydrocarbon mixture is charged to the subsequent chlorinators), particularly in connection with the initial chlorination of a hydrocarbon mixture by residual chlorine contained in hydrogen chloride exit gases from a subsequent stage of chlorination.

The invention furthermore is not limited to treatment of the aromatic compounds disclosed in the above examples but may be employed in connection with the manufacture of other alkyl aromatic sulfonates and especially those of mono- and di-nuclear aromatic hydrocarbons and their simple unsulfonated substitution products. Examples of such compounds are benzene, toluene, naphthalene, diphenyl, phenol, cresol, anisole, phenetole and naphthol. Benzene is preferred.

The yield of desirable alkyl aromatic sulfonates is greatly influenced by the proportion of chlorinated petroleum fraction employed with respect to the amount of aromatic hydrocarbon or unsulfonated derivative thereof used in the preparation of the alkylated aromatic compounds. Theoretically, in order to obtain complete reaction one mol of aromatic compound must be used per atom of chlorine combined with the petroleum hydrocarbon fraction. In practice an amount of aromatic compound in large molecular excess, preferably about twice the weight of chlorinated petroleum is used, as this favors complete reaction of the chlorinated petroleum with the aromatic body, and permits less decomposition and undesirable by-products in the condensation reaction.

The improved results of the present invention are best effected by a condensation of the chlorinated hydrocarbon and aromatic compound with an amount of anhydrous aluminum chloride which is from 1 to 8 per cent of the weight of chlorinated hydrocarbon charge; a better and preferable proportion is from 2 per cent to 5 per cent. In general, with amounts less than 2 per cent, condensation is retarded, while with amounts larger than 5 per cent there is no marked increase in the rate of condensation and

the yield is somewhat decreased, though the quality of condensed product is improved.

The particular manner in which the sulfonation is carried out forms no part of the present invention; this step can be carried out in any suitable manner. For example, sulfuric acids of various strengths such as 66° Bé. sulfuric acid, 100 per cent sulfuric acid, 26 per cent oleum and 65 per cent oleum, and chlor-sulfonic acid may be used as sulfonating agents. The sulfonation may be carried out in the presence of inert solvents or diluents, and sulfonation assistants as, for example, the lower fatty acids and their anhydrides, such as acetic acid and acetic anhydride, or the alkali metal sulfates, such as sodium or potassium sulfate, may be employed. Also, the temperature at which the sulfonation is carried out may vary within wide limits. For example, temperatures as low as about 0° C. and as high as about 140° C. may be employed. In general, the more vigorous the sulfonating agent the lower is the preferred temperature. In most cases the sulfonation is carried out most efficiently at temperatures between 5° and 90° C. For complete sulfonation the sulfonating agent in terms of 100 per cent sulfuric acid may be employed in amounts which range from 0.3 to 5 times or more the weight of the condensation product to be sulfonated. Ordinarily, the extent to which the sulfonation is carried out will vary with the individual material being sulfonated, the duration of the sulfonation, and the use to be made of the sulfonated product. Monosulfonation is preferred.

35 The alkyl aromatic sulfonates may be prepared in the form of their free sulfonic acids or in the form of their salts. Thus they may be prepared in the form of their alkali metal, alkaline earth metal, ammonium, or organic base salts (e. g., 40 amine salts). They are of particular value in the form of their alkali metal and especially sodium salts.

Since certain changes may be made in the process described above without departing from the scope of the invention, it will be understood that the description should be interpreted as illustrative and not in a limiting sense.

This application is a continuation-in-part of my application Serial No. 400,334, filed June 28, 50 1941.

I claim:

1. The method of chlorinating a hydrocarbon mixture of the type of a petroleum distillate boiling over a temperature range lying between 80° C. 55 at atmospheric pressure and 350° C. at 22 mm. absolute pressure, which comprises introducing chlorine gas into the hydrocarbon mixture in liquid phase in an amount not exceeding that effective to chlorinate the hydrocarbon mixture to a degree corresponding to 15% chlorination, and introducing additional chlorine gas into a flowing stream of the resulting partially chlorinated hydrocarbon mixture while maintaining the temperature of the reaction mixture within the range 60 65 60° to 175° C., the total amount of chlorine relative to the amount of hydrocarbon mixture employed being at least sufficient to result in a chlorinated hydrocarbon mixture chlorinated to a degree corresponding to 75% chlorination, 70 whereby a chlorinated hydrocarbon mixture having a low aniline point is obtained.
2. The method of chlorinating a hydrocarbon mixture of the type of a petroleum distillate boiling over a temperature range lying between 80° C. 75 at atmospheric pressure and 350° C. at 22 mm.

absolute pressure, which comprises flowing a stream of the hydrocarbon mixture in liquid phase through a chlorination zone, introducing chlorine gas into the hydrocarbon mixture in said zone in an amount not exceeding that effective to chlorinate the hydrocarbon mixture to a degree corresponding to 15% chlorination while in said zone, and introducing additional chlorine gas into a flowing stream of the resulting partially chlorinated hydrocarbon mixture while maintaining the temperature of the reaction mixture within the range 80° to 155° C., the total amount of chlorine relative to the amount of hydrocarbon mixture employed being at least sufficient to result in a chlorinated hydrocarbon mixture chlorinated to a degree corresponding to 75% chlorination, whereby a chlorinated hydrocarbon mixture having a low aniline point is obtained.

3. The method of chlorinating a hydrocarbon mixture of the type of a petroleum distillate boiling for the most part over a temperature range lying between 180° and 300° C. at atmospheric pressure, which comprises introducing chlorine gas into the hydrocarbon mixture in liquid phase in an amount not exceeding that effective to chlorinate the hydrocarbon mixture to a degree corresponding to 15% chlorination while maintaining the temperature of the reaction mixture within the range 80° to 155° C. and introducing additional chlorine gas at a gage pressure not exceeding 25 pounds per square inch into a flowing stream of the resulting partially chlorinated hydrocarbon mixture while maintaining the temperature of the reaction mixture within the range 80° to 155° C., the total amount of chlorine relative to the amount of hydrocarbon mixture employed being sufficient to result in a chlorinated hydrocarbon mixture chlorinated to a degree corresponding to at least 75% but not more than 200% chlorination, whereby a chlorinated hydrocarbon mixture having a low aniline point is obtained.

4. The method of chlorinating a hydrocarbon mixture of the type of a petroleum distillate boiling for the most part over a temperature range lying between 180° and 300° C. at atmospheric pressure, which comprises flowing a stream of the hydrocarbon mixture in liquid phase through a chlorination zone, introducing chlorine gas at a gage pressure not exceeding 25 pounds per square inch into the hydrocarbon mixture in said zone in an amount not exceeding that effective to chlorinate the hydrocarbon mixture to a degree corresponding to 15% chlorination while in said zone, and introducing additional chlorine gas at a gage pressure not exceeding 25 pounds per square inch into a flowing stream of the resulting partially chlorinated hydrocarbon mixture while maintaining the temperature of the reaction mixture within the range 80° to 155° C., the total amount of chlorine relative to the amount of hydrocarbon mixture employed being sufficient to result in a chlorinated hydrocarbon mixture chlorinated to a degree corresponding to at least 75% but not more than 200% chlorination, whereby a chlorinated hydrocarbon mixture having a low aniline point is obtained.

5. The method of chlorinating a hydrocarbon mixture of the type of a petroleum distillate boiling over a temperature range lying between 80° C. at atmospheric pressure and 350° C. at 22 mm. absolute pressure, which comprises flowing a stream of the hydrocarbon mixture in liquid phase through a plurality of successive chlorina-

tion zones, introducing chlorine gas into the flowing hydrocarbon mixture in said zones, the total amount of chlorine introduced relative to the amount of hydrocarbon mixture being such that the resulting chlorinated hydrocarbon mixture contains an amount of chlorine corresponding to more than 100% chlorination, limiting the amount of chlorine introduced into the hydrocarbon mixture in the first chlorination zone to such an extent that the chlorinated hydrocarbon mixture produced in said zone contains an amount of organically combined chlorine not exceeding that corresponding to 15% chlorination, and introducing additional chlorine gas into the resulting partially chlorinated hydrocarbon mixture in at least one zone while maintaining the temperature of the reaction mixture within the range 60° to 175° C., whereby a chlorinated hydrocarbon mixture having a low aniline point is obtained.

6. The method of chlorinating a hydrocarbon mixture of the type of a petroleum distillate boiling for the most part over a temperature range lying between 180° and 300° C. at atmospheric pressure, which comprises flowing a stream of the hydrocarbon mixture in liquid phase through a chlorination zone, introducing chlorine gas at a gage pressure not exceeding 25 pounds per square inch into the hydrocarbon mixture in said zone in an amount not exceeding that effective to chlorinate the hydrocarbon mixture to a degree corresponding to 15% chlorination while in said zone, and flowing a stream of the resulting partially chlorinated hydrocarbon mixture in liquid phase through at least one additional chlorination zone, at an average velocity of 50 to 20,000 feet per hour while introducing additional chlorine gas at a gage pressure not exceeding 25 pounds per square inch and while maintaining the temperature of the reaction mixture within the range 60° to 155° C., the total amount of chlorine relative to the amount of hydrocarbon mixture employed being sufficient to result in a chlorinated hydrocarbon mixture containing an amount of organically combined chlorine corresponding to 75% to 200% chlorination, whereby a chlorinated hydrocarbon mixture having a low aniline point is obtained.

7. The method of chlorinating a hydrocarbon mixture of the type of a petroleum distillate boiling for the most part over a temperature range lying between 180° and 300° C. at atmospheric pressure, which comprises flowing a stream of the hydrocarbon mixture in liquid phase through a chlorination zone, introducing chlorine gas into the hydrocarbon mixture in said zone in an amount not exceeding that effective to chlorinate the hydrocarbon mixture to a degree corresponding to 15% chlorination while in said zone, and flowing a stream of the resulting partially chlorinated hydrocarbon mixture in liquid phase through at least one additional chlorination zone, at an average velocity of 50 to 20,000 feet per hour while introducing additional chlorine gas and while maintaining the temperature of the reaction mixture within the range 100° to 155° C., the total amount of chlorine relative to the amount of hydrocarbon mixture employed being sufficient to result in a chlorinated hydrocarbon mixture containing an amount of organically combined chlorine corresponding to more than 100% but not more than 150% chlorination, whereby a chlorinated hydrocarbon mixture having a low aniline point is obtained.

8. The method of chlorinating a hydrocarbon mixture of the type of a petroleum distillate boil-

ing for the most part over a temperature range lying between 180° and 300° C. at atmospheric pressure, which comprises flowing a stream of the hydrocarbon mixture in liquid phase through a chlorination zone, introducing chlorine gas into the hydrocarbon mixture in said zone in an amount not exceeding that effective to chlorinate the hydrocarbon mixture to a degree corresponding to 15% chlorination while in said zone, and flowing a stream of the resulting partially chlorinated hydrocarbon mixture in liquid phase through at least one additional chlorination zone, at an average velocity of 50 to 1000 feet per hour while introducing additional chlorine gas and while maintaining the temperature of the reaction mixture within the range 100° to 155° C., the total amount of chlorine relative to the amount of hydrocarbon mixture employed being sufficient to result in a chlorinated hydrocarbon mixture containing an amount of organically combined chlorine corresponding to more than 100% but not more than 200% chlorination, whereby a chlorinated hydrocarbon mixture having a low aniline point is obtained.

9. The method of chlorinating a hydrocarbon mixture of the type of a petroleum distillate boiling for the most part over a temperature range lying between 180° and 300° C. at atmospheric pressure, which comprises flowing a stream of the hydrocarbon mixture in liquid phase, maintained at a temperature within the range 60° to 175° C., through a chlorination zone, introducing chlorine gas into the hydrocarbon mixture in said zone in an amount not exceeding that effective to chlorinate the hydrocarbon mixture to a degree corresponding to 15% chlorination while in said zone, and flowing a stream of the resulting partially chlorinated hydrocarbon mixture in liquid phase through at least one additional chlorination zone of greater length than the effective average width of the stream, at an average velocity of 50 to 5000 feet per hour while introducing additional chlorine gas and while maintaining the temperature of the reaction mixture within the range 100° to 175° C., the total amount of chlorine relative to the amount of hydrocarbon mixture employed being sufficient to result in a chlorinated hydrocarbon mixture containing an amount of organically combined chlorine corresponding to at least 75% but not more than 200% chlorination, whereby a chlorinated hydrocarbon mixture having a low aniline point is obtained.

10. The method of chlorinating a hydrocarbon mixture of the type of a petroleum distillate boiling for the most part over a temperature range lying between 180° and 300° C. at atmospheric pressure, which comprises flowing a stream of the hydrocarbon mixture in liquid phase maintained at a temperature within the range 60° to 175° C., through a chlorination zone, introducing chlorine gas at a gage pressure not exceeding 25 pounds per square inch into the hydrocarbon mixture in said zone in an amount not exceeding that effective to chlorinate the hydrocarbon mixture to a degree corresponding to 15% chlorination while in said zone, and flowing a stream of the resulting partially chlorinated hydrocarbon mixture in liquid phase through at least one additional chlorination zone, at an average velocity of 50 to 600 feet per hour while introducing additional chlorine gas at a gage pressure not exceeding 25 pounds per square inch and while maintaining the temperature of the reaction mixture within the range 110° to 155° C., the total amount of chlorine relative to the amount of

hydrocarbon mixture employed being sufficient to result in a chlorinated hydrocarbon mixture containing an amount of organically combined chlorine corresponding to more than 100% but not more than 150% chlorination, whereby a chlorinated hydrocarbon mixture having a low aniline point is obtained.

11. The method of chlorinating a kerosene fraction of a petroleum distillate of the Pennsylvania petroleum type, which comprises flowing a stream of the kerosene in liquid phase through a chlorination zone, introducing chlorine gas into the kerosene in said zone in an amount not exceeding that effective to chlorinate the kerosene to a degree corresponding to 15% chlorination while in said zone, and flowing a stream of the resulting partially chlorinated kerosene in liquid phase through at least one additional chlorination zone of greater length than the effective average width of the stream, at an average velocity of 50 to 5000 feet per hour while introducing additional chlorine gas at a gage pressure not exceeding 25 pounds per square inch and while maintaining the temperature of the reaction mixture within the range 110° to 155° C., the total amount of chlorine relative to the amount of kerosene employed being sufficient to result in a chlorinated kerosene containing an amount of organically combined chlorine corresponding to more than 100% but not more than 150% chlorination, whereby a chlorinated kerosene having a low aniline point is obtained.

12. In the manufacture of alkyl aromatic sulfonates by chlorinating a hydrocarbon mixture of the type of a petroleum distillate boiling over a temperature range lying between 80° C. at atmospheric pressure and 350° C., at 22 mm. absolute pressure, condensing a resulting mixture of chlorinated hydrocarbons with an aromatic compound, and sulfonating a resulting mixture of alkyl aromatic compounds, the improvement which comprises flowing a stream of the hydrocarbon mixture in liquid phase through a chlorination zone, introducing chlorine gas into the hydrocarbon mixture in said zone in an amount not exceeding that effective to chlorinate the hydrocarbon mixture to a degree corresponding to 15% chlorination while in said zone, and introducing additional chlorine gas into a flowing stream of the resulting partially chlorinated hydrocarbon mixture while maintaining the temperature of the reaction mixture within the range 60° to 175° C., the total amount of chlorine relative to the amount of hydrocarbon mixture employed being at least sufficient to result in a chlorinated hydrocarbon mixture chlorinated to a degree corresponding to 75% chlorination.

13. In the manufacture of alkyl sulfonates by chlorinating a hydrocarbon mixture of the type of a petroleum distillate boiling over a temperature range lying between 80° C. at atmospheric pressure and 350° C., at 22 mm. absolute pressure, condensing a resulting mixture of chlorinated hydrocarbons with an aromatic compound, and sulfonating a resulting mixture of alkyl aromatic compounds, the improvement which comprises flowing a stream of the hydrocarbon mixture in liquid phase through a chlorination zone, introducing chlorine gas into the hydrocarbon mixture in said zone in an amount not exceeding that effective to chlorinate the hydrocarbon mixture to a degree corresponding to 15% chlorination while in said zone, and flowing a stream of the resulting chlorinated hydrocarbon mixture in liquid phase through at least one additional chlorina-

ton zone at an average velocity of 50 to 5000 feet per hour while introducing additional chlorine gas at a gage pressure not exceeding 25 pounds per square inch and while maintaining the temperature of the reaction mixture within the range 80° to 155° C., the total amount of chlorine relative to the amount of hydrocarbon mixture employed being sufficient to result in a chlorinated hydrocarbon mixture containing an amount of organically combined chlorine corresponding to more than 100% but not more than 200% chlorination.

14. In the manufacture of alkyl benzene sulfonates by chlorinating a kerosene fraction of a petroleum distillate of the Pennsylvania petroleum type, condensing the resulting chlorinated kerosene with benzene, and sulfonating the resulting mixture of alkyl benzenes, the improvement which comprises flowing a stream of the kerosene in liquid phase through a chlorination zone, introducing chlorine gas into the hydrocarbon mixture in said zone in an amount not exceeding that effective to chlorinate the hydrocarbon mixture to a degree corresponding to 15% chlorination while in said zone, and flowing a stream of the resulting partially chlorinated hydrocarbon mixture in liquid phase through at least one additional chlorination zone of greater length than the effective average width of the stream, at an average velocity of 50 to 5000 feet per hour while maintaining the temperature of the reaction mixture within the range 100° to 155° C., the total amount of chlorine relative to the amount of hydrocarbon mixture employed being sufficient to result in a chlorinated hydrocarbon mixture containing an amount of organically combined chlorine corresponding to at least 75% but not more than 150% chlorination.

15. In the manufacture of alkyl benzene sulfonates by chlorinating a kerosene fraction of a petroleum distillate of the Pennsylvania petro-

leum type, condensing the resulting chlorinated kerosene with benzene, and sulfonating the resulting mixture of alkyl benzenes, the improvement which comprises flowing a stream of the kerosene in liquid phase through a chlorination zone, introducing chlorine gas into the kerosene in said zone in an amount not exceeding that effective to chlorinate the kerosene to a degree corresponding to 15% chlorination while in said zone while maintaining the temperature of the reaction mixture within the range 80° to 155° C., and flowing a stream of the resulting partially chlorinated kerosene in liquid phase through at least one additional chlorination zone, at an average velocity of 50 to 600 feet per hour while introducing additional chlorine gas at a gage pressure not exceeding 25 pounds per square inch and while maintaining the temperature of the reaction mixture within the range 110° to 155° C., the total amount of chlorine relative to the amount of kerosene employed being sufficient to result in a chlorinated kerosene containing an amount of organically combined chlorine corresponding to more than 100% but not more than 150% chlorination.
